US00D989809S

(12) **United States Design Patent** (10) Patent No.: **US D989,809 S**
Butcher et al. (45) Date of Patent: **** Jun. 20, 2023**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, Los Gatos, CA (US);
Joseph Chan, San Francisco, CA (US);
Bronwyn Anne Jones, San Francisco,
CA (US); **Ieyuki Kawashima**,
Pleasanton, CA (US); **Stephen O.**
Lemay, Palo Alto, CA (US); **Aled**
Williams, Llandeilo (GB)

(73) Assignee: **Apple Inc.**, Cupertino, CA (US)

(**) Term: **15 Years**

(21) Appl. No.: **29/800,051**

(22) Filed: **Jul. 19, 2021**

Related U.S. Application Data

(63) Continuation of application No. 29/746,888, filed on Aug. 18, 2020, now Pat. No. Des. 925,601, which is a continuation of application No. 29/680,379, filed on Feb. 15, 2019, now Pat. No. Des. 894,940, which is a continuation of application No. 29/657,343, filed on Jul. 20, 2018, now Pat. No. Des. 841,050, which is a continuation of application No. 29/582,454, filed on Oct. 27, 2016, now abandoned.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface, that form no part of the claimed design.
